Tadayuki Nagamori, 851 Yukigaya-cho, Tokyo, Japan

Filed Oct. 31, 1961, Ser. No. 67,315

Term of patent 14 years

(Cl. D93—4)

FIG. 1 is a perspective view of an illuminable handle for a screwdriver or the like embodying my new design; FIG. 2 is an elevational view thereof;

FIG. 3 is an elevational view taken from the right of FIG. 2;

FIG. 4 is a top plan view thereof;

FIG. 5 is a bottom plan view thereof; and

FIGS. 6 and 7 are sectional views taken on lines 6—6 and 7—7, respectively, of FIG. 2.

The screwdriver is shown in broken lines in FIG. 2 for illustrative purposes only.

I claim:

The ornamental design for an illuminable handle for a screwdriver or the like, as shown.
